US00D496984S1

(12) **United States Design Patent** (10) Patent No.: **US D496,984 S**
Costa et al. (45) Date of Patent: **** Oct. 5, 2004**

(54) **WATER PURIFIER**

(75) Inventors: **Alvin Costa**, Tiverton, RI (US);
Richard T. Coffey, Pompano Beach, FL (US); **Michael Pereira**, Smithfield, RI (US); **Daniel Nelsen**, Providence, RI (US); **Thomas Parent**, Providence, RI (US); **Christopher Kampf**, Cranston, RI (US); **Ryan White**, Georgetown, MA (US)

(73) Assignee: **Zodiac Pool Care, Inc.**, Pompano Beach, FL (US)

(**) Term: **14 Years**

(21) Appl. No.: **29/180,122**

(22) Filed: **Apr. 18, 2003**

(51) LOC (7) Cl. **23-01**

(52) U.S. Cl. **D23/207**

(58) Field of Search **D23/207, 209; 210/238, 341, 470**

(57) **CLAIM**

The ornamental design for a water purifier, as shown and described.

DESCRIPTION

FIG. 1 is a front elevational view of the new design for a water purifier;

FIG. 2 is a back elevational view of the new design for a water purifier;

FIG. 3 is a perspective view of the new design for a water purifier;

FIG. 4 is a right side elevational view of the new design for a water purifier;

FIG. 5 is a left side elevational view of the new design for a water purifier;

FIG. 6 is a top plan view of the new design for a water purifier; and,

FIG. 7 is a bottom plan view of the new design for a water purifier.

1 Claim, 7 Drawing Sheets
